UNITED STATES PATENT OFFICE.

THEODORE C. SMITH, OF PHILADELPHIA, PENNSYLVANIA.

ATTACHABLE ELECTRIC SWITCH FOR CONNECTER PLUGS.

Application filed January 19, 1923. Serial No. 313,611.

To all whom it may concern:

Be it known that I, THEODORE C. SMITH, a citizen of the United States, residing at Philadelphia, in the county of Philadelphia and State of Pennsylvania, have invented new and useful Improvements in Attachable Electric Switches for Connecter Plugs, of which the following is a specification.

My invention relates to attachable electric switches for connecter plugs, and has for its primary object the provision of such a switch which will fit universally the connecter plugs made by different manufacturers.

It is to be understood that the connecter plug referred to is a plug usually having two contact clips that fit on the terminals of the electrical appliances, such as sad irons, toasters and the like, and is one of the elements of the customary cord which also includes the flexible feed wires and an attachment plug, the latter being used to make connection with the service lines through the usual socket or receptacle.

Heretofore the methods employed for making and breaking the electrical connections with the appliances consisted of the following:—

1. The use of a connecter plug usually having two enclosed spring grip contacts for detachable connection with the appliance terminals.

2. The use of a switch on the wires attached to the connecter plug above mentioned and positioned some distance beyond the plug.

3. The use of a switch within the connecter plug.

4. The use of a cord permanently attached to the appliance and depending upon the detachable attachment plug or socket or wall switch for opening and closing the circuit.

Where a detachable connecter plug is used such plug becomes so hot after a short period of use that it is uncomfortable to handle and the operations necessary to attach or detach the plug are so slow that the resultant arc often burns out the contact clips and terminals.

5. If a switch is used on the wires of the cord it is in an inconvenient position and adds a drag to the cord thus preventing the free operation of an iron.

Having the switch within the connecter plug should any part of the housing or casing, the switch mechanism or contacts be-

come damaged or disarranged it usually is necessary that the entire switch connecter plug be replaced by a complete new one.

Where a cord permanently fixed to the appliance is used it is exceedingly inconvenient to detach or replace the attachment plug each time the circuit is to be broken or completed and if the wall or socket switch is utilized considerable time and effort is lost.

Among other features the invention comprehends overcoming the disadvantages above enumerated by providing a switch which is attachable to the connecter plug in such a position as to be readily accessible by the operator thereby saving time and effort and making it unnecessary to remove either the connecter plug or attachment plug. Such an arrangement also overcomes the necessity of discarding the switch mechanism when the connecter plug is damaged or vice versa.

I aim to provide a switch, comprising principally a housing or casing and a switch mechanism, in connection with a connecter plug so arranged as to be practically a unitary structure while permitting the separation of the switch from the plug for purposes of repair or replacement.

Another object of the invention contemplates the provision of means to indicate when the electric current is on and off.

A further object of the invention is to provide attaching means of unique construction whereby the casing with its enclosed mechanism may be readily and quickly removed or replaced.

A still further object of the invention is the provision of a switch of the character set forth which will fit universally the flexible cord supporting springs of different configurations produced by various manufacturers.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a side elevation of my attachable switch with a portion of the switch

operating ring broken away and showing the switch attached to one of the body sections or members the other body member having been dispensed with for purposes of 5 illustration.

Fig. 2, is a longitudinal sectional view of the switch embodied in my invention.

Fig. 3, is an inner end view thereof.

Fig. 4 is a section at the line 4—4 of 10 Fig. 1.

Fig. 5, is an end view opposite to Fig. 4 of the switch panel.

Fig. 6, is a section of the switch panel and its component parts at the line 6—6 15 of Fig. 4.

Fig. 7, is a section at the line 7—7 of Fig. 5.

Referring more particularly to the drawings it will be apparent to those skilled in 20 the art, that Fig. 1 shows one of two similar body members of insulating material 10 which when secured together by suitable means complete the connector plug body. In the particular embodiment illustrated 25 the interior of the plug body is divided into spring clip receiving chambers 11 and 12 which clips (not shown) confront the openings 13 and 14 through which pass the terminals of the electrical appliance and these 30 chambers communicate with an arcuate or circular groove 15 from which leads an opening 16 of smaller diameter than the groove 15 so as to form a shoulder 17.

The reference numeral 18 represents the 35 switch housing or casing including a body 19 preferably tubular in cross section consisting of side walls 20, a bottom end wall 21 having an opening 22 therethrough preferably surrounded by a flange 23 which also 40 preferably projects outward, as shown. A tubular coupling member 24 open at both ends projects through the hole 22 and has threaded connection with the body 19 so that 45 said coupling member may be threaded in and out. At the outer end of this coupling member is an outwardly projecting circular flange 25 knurled or roughened on one or both of its faces as indicated at 26 and plainly shown in Fig. 3.

With the body 18 coacts a cap or other member 27 which also is preferably tubular in cross section and is adapted for detachable connection to the body member 18 and for convenience of illustration means for connecting these two members is here shown as threads 28 but any equivalent means may be substituted, as for instance the bayonet joint. This other member or cap 27 consists of side walls 29 and a top or end wall 30 having a hole 31 therein through which projects one end of the supporting spring 32 carrying the ordinary ferrule 33 at its outer free end.

The supporting spring being of spiral formation may be attached to the switch

after the manner of a screw by forcing the free end into the hole 31 so as to separate adjacent coils and revolving the spring. As the interior diameter of the cap 27 is great enough to accommodate the springs of 70 largest diameter used and as the hole 31 therein is smaller than the diameter of the smallest springs used the switch is adapted to fit universally the springs produced by the various manufacturers. 75

From the foregoing description it will be seen that by screwing the coupling member 24 outward to space the flange 25 thereof of some distance from the end or bottom wall 21 of the body 19 the flange 25 can 80 then be inserted in the groove 15 of one of the plug body members 10 and the other plug body member then superimposed thereon thus entirely enclosing the flange 25. Then by grasping the body member 19 and the connector plug body in such way as to tend to pull them apart the knurled or roughened surface of the flange 25 will grip the shoulder 17 of the plug body or engage it with sufficient friction to prevent rotation 85 of the coupling member 24 during rotation of the casing 19, such rotation screwing said casing body onto the coupling member until the bottom or end wall 21 engages the exterior surface of the end of the plug body 90 thereby securely attaching the casing to the connector plug. 95

In the particular form of switch herein illustrated a panel 34 of suitable insulating material is utilized and preferably has a 100 reduced portion to snugly fit within the casing body 19 and be properly positioned by contact of the shoulder 35 with the edge of said casing body. In the panel 34 are mounted a pair of switch terminals 36 and 105 37 each having a head 38 projecting from one or the inner face of said panel while the other end is swedged in any suitable manner, as for instance, like a rivet to form a secondary head 39 to prevent accidental 110 displacement of the terminals. The secondary heads of these switch terminals are located within recesses 40 formed in the other face of the panel 34 and adapted to lie within the recesses 40, one of said screws as 41 115 being used for connecting one of the flexible lead in or service wires (not shown) to the switch mechanism while the other screw as 42 is used for connecting another wire (not shown) to the switch mechanism and this wire passes through a notch 43 in the panel and then through the connecting member 24 into the plug body where it is attached to one of the spring clips (not shown) 120 as for instance the one within the chamber 12. Another screw 44 is threaded into the panel but does not pass therethrough or contact with any contact member or conducting agent of the switch mechanism the same being used for connecting the other service or 125 130

lead in wire (not shown) to the switch as well as a wire which passes through the notch 45 in the panel and then through the connecting member 24 into the plug body 5 where it is attached to the other spring clip (not shown) located within the chamber or compartment 11.

The oscillating switch arm 46 is mounted on a screw 47 threaded into the axial center 10 of the panel 34 with a spacing member 48 between the arm and face of the panel to permit the oscillating arm to actuate freely and at the same time properly contact with the terminal heads. To one end of this oscillating switch arm is fixed one end of the helical spring 49 the other end being fixed to an attaching member 50 of insulating material or insulated from the switch casing in some suitable manner, said attaching member 20 being carried by an operating ring 51 of insulating material which surrounds the switch casing body the same being rotatably and slidably mounted on said body. The attaching member 50 operates within the inclined slot 25 151 in the casing body so that as the operating ring 51 is rotated it naturally slides longitudinally of the casing. The movement of the operating ring is such that the spring 49 may be moved across the center of the 30 oscillating switch arm 46 when the latter is in either of its two positions and when in its inoperative position, as shown in Fig. 4, its movement is limited by a stop 52 whereas when it is moved toward its operative position which would be at right angles to that shown in Fig. 4 its movement is arrested by a stop 53.

The operating ring 51 having a sliding movement upon a switch casing it may be 40 utilized as a means for indicating the condition of the switch, namely, whether in an operative or an inoperative position. This may be done in a number of different ways but consists mainly in simultaneously covering and uncovering portions of the exterior surface of the switch casing and if these operations of the exterior surface are provided with indication devices which will be covered and uncovered by the operating ring then the operator may readily ascertain whether or not the electric current is on or off.

One method of accomplishing the above result is herein illustrated and consists in 55 providing two differently colored zones or stripes 54 and 55 of such width that when the operating ring has been moved the full distance in one direction or the other one of the stripes will be exposed and the other covered. The stripe numbered 54 may be of red or other suitable color and the stripe 60 55 of green or other suitable color in which case the operating ring 51 will be in the position shown in Fig. 1 when the current 65 is turned off, the green stripe 55 being visible

will indicate to the operator that such is the case, but when the operating ring is moved to a position such as shown in Fig. 2 the green stripe 55 will be covered and the red stripe 54 will be visible thus indicating the 70 current has been turned on.

From the foregoing description it will now be apparent to those skilled in the art that I have provided an exceedingly simple although strong and durable structure the 75 parts of which are easily and quickly assembled. Further a switch of this character is readily attachable to connector plugs of different make because the circular grooves 15 and the openings 16 of the different connector plugs are substantially the same and since the diameter of the flange 23 may be the same as the smallest hole in such plugs while any variation in thickness of the end wall of the plug body is provided 80 for by the adjustability of the connecting member 24. As hereinbefore stated the flange 25 of the connecting member 24 in conjunction with the bottom or end wall 21 of the casing body acts as the attaching medium for the switch and connector plug requiring no tools to attach or remove one to or from the other.

As mentioned heretofore the switch is detachably connected with the connector plug 95 and therefore if any part of said connector plug or if any part of the switch is damaged said switch may be disengaged and the damaged member replaced without the necessity of purchasing a complete switch and 100 connector plug.

Of course I do not wish to be limited to the exact details of construction as herein shown as these may be varied within the limits of the appended claims without departing from the spirit of my invention.

Having thus fully described my invention, what I claim as new and useful is:—

1. As an article of manufacture, a switch including a casing, a switch mechanism therein and a coupling member provided with a flange and having threaded engagement with the casing whereby a portion of a connector plug may be gripped between the casing and said flange to detachably fasten the switch to the connector plug.

2. The combination with a connector plug including separable members forming a plug body having an opening communicating with a circular groove of larger diameter than the opening to produce a shoulder, of a switch casing contacting with said connector plug in the region of the opening and means carried by the casing and adjustable relative thereto with a portion positioned in the groove to grip the shoulder for detachably fastening the casing to the connector plug.

3. The combination with a connector plug including separable members forming a plug

body having an opening communicating with a circular groove of a larger diameter than the opening to produce a shoulder, of a coupling member positioned in the circular groove of said plug body for coaction with the shoulder and having a portion projecting through the opening and a casing adjustably mounted on the projecting portion of said member and adapted to contact with the plug body in the region of the opening to detachably fasten the casing to the connector plug.

4. The combination with a connector plug including separable members forming a plug body having an opening communicating with a circular groove of a larger diameter than the opening to produce a shoulder, of a coupling member to pass through the opening and having a flange at one end for insertion in the groove to coact with the shoulder and a casing having threaded connection with said member and adapted to coact with the connector plug in the region of the opening for drawing the flange against the shoulder to detachably connect the casing to the connector plug.

5. The combination with a connector plug including separable members forming a plug body having an opening communicating with a circular groove of a larger diameter than the opening to produce a shoulder, of a tubular coupling member passing through the opening in the plug body, a flange carried by said member and positioned within the groove for coaction with the shoulder, said flange having a knurled or roughened surface for frictional engagement with said shoulder, a casing body having an end wall with a hole therethrough and open at the opposite end, a flange surrounding said hole, said casing body having threaded engagement with the coupling member and adapted to coact with the connector plug to draw the flange against the shoulder for detachably connecting the casing body to said connector plug, said casing body having an inclined slot, a ring slidably and rotatably mounted on the casing body and provided with means passing through the slot for connection with a switch mechanism adapted to be housed in the casing body, a cap having threaded engagement with the casing body, said cap having an opening in its end wall and a supporting spring passing through the open-

ing in the cap and supported by said cap. 55
6. In a switch, the combination of a casing, a switch mechanism therein, two parallel differently colored stripes encircling said casing and a ring for actuating the switch mechanism, said ring being rotatably and 60 slidably mounted on the casing and movable over said stripes for simultaneously uncovering one and uncovering the other of said stripes to indicate when the current is on and off.

7. An electric switch having means for attaching externally to a connector plug, said means using the coil spring retaining socket of the connector plug as a retaining socket for the switch.

8. In a device of the class mentioned, a switch, and means to detachably fasten said switch to a connector plug which latter includes a body and contact clips enclosed in said body for coaction with the terminals 75 of electrical appliances.

9. The combination with a connector plug including a body and a pair of contact clips therein for registration with a pair of terminals, of a switch casing, and means carried thereby for detachably connecting said casing to the connector plug.

10. In a device of the character stated, an electric switch, and means to universally attach it to different connector plugs which 85 in turn are adapted to be detachably mounted directly on electrical appliances.

11. In a device of the character stated, a switch, and means to universally attach it to different supporting springs which 90 in turn are adapted to be mounted on connector plugs each of the latter including a body and contact clips therein for registration with the terminals of an electrical appliance.

12. The combination with a connector plug for direct detachable connection to an electrical translating device and including separable members constituting a body and contact clips housed by said body for coaction with the terminals on the translating device, of a switch comprising a casing and a circuit making and breaking mechanism, and means to temporarily fasten the switch to the connector plug.

In testimony whereof, I have hereunto affixed my signature.

THEODORE C. SMITH.
